ARCHIBALD GRIEVE, OF WESTPORT, CONNECTICUT, ASSIGNOR TO CHARLES H. KEMPER, INC., OF WESTPORT, CONNECTICUT, A CORPORATION OF CONNECTICUT.

FUSE.

Application filed February 4, 1921. Serial No. 442,515.

To all whom it may concern:

Be it known that I, ARCHIBALD GRIEVE, a subject of the King of Great Britain, residing at Westport, in the county of Fairfield 5 and State of Connecticut, have invented certain new and useful Improvements in Fuses, of which the following is a specification.

My invention relates to fuses, and particularly to refillable cartridge fuses of the blade 10 type. Among the objects of my invention may be particularly mentioned—first, the provision of an end construction for the fuse such that the detachable parts may be removed and securely replaced without the 15 use of tools of any description, while at the same time insuring an excellent contact between the terminal element and the fuse strip; second, the provision of a removable element at the end of the fuse casing, which, 20 while comprising a group of independent elements, may be readily handled as a unit and thus minimize the danger of loss of parts and delay in handling during the renewal of the fuse strip; third, the reduction 25 of the number of removable end parts to the least possible number consistent with efficient protection; fourth, the exterior display of a rated end of the fuse strip, while at the same time preventing the dangerous 30 escape of hot gases through the passage in which said end of the fuse strip lies; fifth, the prevention of gas escape through the threaded connection between the screw ferrule and end bushing; sixth, the provision 35 of a gas expansion chamber between the fuse chamber and gas vents to prevent the escape of molten metal or flame through the latter, and in this connection particularly a construction which permits the expansion 40 chamber to vary with fuses of different capacities within the range of the fuse structure, without, however, lessening the security against gas escape; seventh, the provision 45 of an extended gas escape passage between the expansion chamber and vent, by means of which the gases are compelled to change their direction of travel several times and to pass in contact with extended cooling 50 surfaces before they emerge through the vent or vents; eighth, a construction of the parts such that the insertion of a fuse strip of a capacity greater than that for which the fuse is designed is rendered impossible; ninth, the secure anchorage of an end bushing 55 to the cartridge casing in a manner

which prevents the entry of gases between the bushing neck and casing wall to the injury of the latter; tenth, the provision of various features of improved construction hereinafter pointed out or shown in the accompanying drawings, in which—

Fig. 1 is a broken longitudinal side elevation of a fuse in which my invention is embodied in one form;

Fig. 2 is a longitudinal section therethrough;

Fig. 3 is a perspective of the casing element with end caps and associated parts removed, and showing a fuse strip partially inserted;

Fig. 4 is a longitudinal section on the line 4—4, Fig. 2, drawn to a larger scale;

Fig. 5 is a section on the line 5—5, Fig. 4; and

Fig. 6 is a perspective of a gas-deflecting washer.

To illustrate the invention, which is susceptible of embodiment in various modified constructions, I have shown a fuse comprising a tubular casing 7 of fiber, or other suitable insulating material, having permanently secured in the opposite ends thereof metallic bushings 8 and 9. Each bushing is provided with a neck 10 which is forced into the end of the fiber casing 7 and riveted in position at 11. The exterior face of the neck is preferably serrated as shown, in order to not only grip the material of the casing, but also to prevent the escape of gas between the casing and the bushing neck on the blowing of the fuse. The end of each bushing has an integral end closure diaphragm 12 provided with an opening 13, through which the end of the fuse strip 14 may be passed. A stud 15 secured to the diaphragm 12 forms the pivot on which a shutter 16 is mounted. This shutter normally closes the opening 13 in the diaphragm save for the narrow passageway afforded for the exit of the fuse strip therethrough from the fuse chamber. 100 A second stud 25 carried by the diaphragm 12 on the opposite side of the opening 13, forms a stop which limits the movement of the shutter in one direction. The ends 17 and 18 of the strip emerging from the opposite ends of the fuse chamber are angled over the shutters 16, the end 18 having a terminal extension 19. This extension 19 is bent back into a shallow groove 20 formed in the exterior of the bushing and adjacent por-

tion of the casing 7, and is of such length that its free end, which bears an indication of its rating, lies exposed beyond the margin of the end ferrule 21.

5 The removable end members of the fuse comprise in addition to the screw ferrule 21, the terminal blades 22, by which the fuse is electrically connected to the clips of the fuse holder in adjusted position. These 10 blades are provided with circular base flanges or discs 23, which rest directly upon the bent-over ends 17 and 18 of the fuse strip and make contact therewith. In order to secure the alinement of the blades at opposite ends of the fuse, holes 24 are punched in the base flanges 23 and register with the projecting heads of the studs 15 and 25 on the bushings 8 and 9. The base flange of each blade 22 is thus spaced from the shutter 16 and from the end of the bushing, thus affording an expansion chamber 26, into which the gases from the fuse chamber enter on the blowing of the fuse. In order to permit the escape of the gases from the expansion chamber, the holes 24 in the base flanges 23 are of greater diameter than the heads of the studs 15 and 25, and the latter may be of cone shape, as indicated, to afford sufficient passageway for this purpose. Inasmuch as the direct escape of the hot gases, even as cooled in the expansion chamber, would be dangerous, I provide a gas deflecting and cooling washer 27 slightly spaced by diminutive studs 28 from the outer face of the base flange 23, and provided with a central slot 29, which permits the washer to be passed over the blade 22, but closely engaging the latter to prevent the escape of gases at this point. The 40 washer is pierced by perforations 30 of any suitable size and number to permit the gases to pass therethrough. It will be obvious that the gases are thus forced to spread out between the top of the base flange 23 of the blade 22 and the inner face of the washer 27 in order to pass to the outer face of the latter through the holes 30.

Further restricting the passage of the gases is a relatively light metal thimble 31, the marginal flange of which closely embraces the washer 27, the base flange 23 of the blade 22, the shutter 16, and the reduced end 32 of the bushing 9. This snug fit of the thimble flange upon the reduced end 32 of the bushing not only confines the gases to the expansion chamber 26, thus forcing them to pass out through the perforations 30, but it also prevents the escape of the gases to the threaded area of the bushing 60 and ferrule—a feature of first importance in a renewable fuse, since the entry of the hot gases between the ferrule threads is very apt to cause the latter to bind so hard that the unscrewing of the ferrule becomes a practical impossibility. The thimble 31 ef-

fectually prevents this. The gases passing through the holes 30 in the washer, and coming into contact with the inner face of the thimble end, are again deflected by the latter and are forced to flow toward the blade 22, where they escape through the slot 33 in the thimble end at a temperature and pressure so reduced as to prevent injury to adjacent objects. The notch 34 (Fig. 1) in the marginal flange of the thimble 75 through which the rated end 19 of the fuse strip passes to the channel 20, so closely fits the strip that when the parts are assembled practically no gas escapes at this point.

To hold the detachable end elements of the fuse assembled, I provide the ferrules 21 with interiorly threaded skirts, which engage the externally threaded area 35 of the bushing, while the inwardly turned flange 36 bears upon the marginal area of the end 80 face of the thimble 31. It is obvious that on screwing up the ferrule 21 its flange 36 exerting pressure through the thimble 31 and washer 27, forces the base flange 23 of the blade terminal 22 firmly down upon the bent-over end of the fuse strip and establishes a good electrical contact between these parts without any tendency to injure the fuse strip. At the same time the screw ring holds the thimble 31 in such close 85 engagement with the reduced end 32 of the bushing that the lateral escape of the gases to the threaded area 35 is substantially prevented, and no appreciable gas escape occurs in this direction as above stated. The 90 central opening of the ring leaves the central area of the thimble 31 unsupported, so that when the gases under pressure escape through the holes 30 in the washer 27 to the space between the latter and the thimble, the 95 latter is slightly distorted outward and permits the flow of gases to the vent passage 33. This flexion of the thimble serves the purpose of a reducing valve, which further limits the pressure of the gases coming from 100 the expansion chamber and now substantially cooled by their contact with the extended metal surfaces in contact with which they have been forced to travel.

It is obvious that the circuitous path 115 which the gases are thus forced to travel in contact with heat absorbing and radiating metallic surfaces, extracts from the gases substantially all their dangerous heat, so that upon their exit they are at a temperature below that at which they are likely to ignite any inflammable material in their immediate neighborhood, or to injure adjacent equipment. Moreover, the expansion intermediate the fuse chamber and the vent, and the reducing valve affect secured by the distortion of the end of the thimble 31, practically eliminate the dangerous pressure at which the gases would otherwise escape. The shallow groove 20 in which the exposed 120 125 130

end 19 of the fuse strip lies, is substantially filled by the latter, while the pressure of the thimble 31 and the ferrule 21 against the end of the fuse strip substantially seals the 5 groove 20 against the escape of gases at this point. Moreover, it will be noted that the groove 20 is situated at the side of the expansion chamber opposite that at which the gases enter the latter through the opening 10 from the fuse chamber, consequently they readily pass out through the holes 24 before reaching the groove.

The diameter of the skirt of the thimble is so predetermined with relation to the 15 diameter of the reduced end of the thimble that when the thimble is in position on the latter its skirt hugs the reduced area 32 so closely that the escape of gas at this point is substantially, if not absolutely, prevented. 20 Again, the zigzag path which the gases must travel to escape at the edge of the skirt of the thimble impedes their travel and further tends to prevent their passage in this direction. It may be pointed out that the reduced end 32 of the bushing is cylindrical, 25 and the skirt of the thimble similarly shaped so that the latter may accommodate itself to the various positions assumed by it as a result of different thicknesses of the fuse 30 strip for fuses of different capacity, within the range of the fuse cartridge, without the loss of the security against gas escape at this point.

Mechanically, the operation of renewal is 35 simple. Upon unscrewing the ferrule 21 the blade 22 carrying the thimble 31 and washer 27 is removed with the ferrule, and these parts form a unit and remain assembled. Even should the ferrule become detached 40 from the blade, the parts associated with the latter, viz., the thimble 31 and washer 27, remain assembled on the blade by reason of the frictional engagement between these parts. After the ferrule, blade, and associated parts have been removed, the shutter 16 is readily swung open to expose the 45 opening 13 through which the blown fuse parts may be removed and a new fuse strip inserted. To re-assemble the parts it is only necessary to insert the new fuse strip, close the shutters, angle over the fuse ends, position the blades on the studs, and screw up the ferrules, thus mechanically and electrically connecting the parts again for re-use. In 50 order to facilitate the manipulation of the ferrules, they may be externally knurled, as shown in Fig. 1. It is obvious that the present construction has the marked advantage over all the renewable fuses now on the 55 market, that to effect the renewal operation no tools whatever are required, since the unscrewing and screwing up of the ferrules is accomplished solely by hand. The fuse strip requires no connection by binding or 60 clamping screw to the blade element, while

the bearing contact with the base flange of the blade is more extensive than that usually provided for between the fuse and blade, and results in a better electrical connection between these parts. Moreover, the screwing-up action has no tendency to distort or rupture the portion of the fuse strip against which the base flange of the blade bears. 70

As above stated, various modifications in detail of construction will readily occur to 75 those skilled in the art, without departing, however, from the underlying conceptions which I claim as my invention.

I claim—

1. A cartridge fuse having an end construction comprising a blade contact with base flange adapted to rest upon and make contact with the end of a fuse strip, a thimble fitting over the blade and having a marginal flange embracing the blade base, and a gas-deflecting washer interposed between said base and the end of the thimble. 80

2. A cartridge fuse having an end construction comprising a blade contact with base flange adapted to rest upon and make contact with the end of a fuse strip, a thimble fitting over the blade and having a marginal flange embracing the blade base, and a gas-deflecting washer interposed between said base and the end of the thimble, 90 together with a draw-up ring embracing the thimble and serving to effect the assembly of the parts at the end of the fuse. 95

3. A cartridge fuse having an end construction comprising a blade contact with base flange adapted to rest upon and make contact with the end of a fuse strip, a thimble fitting over the blade and having a marginal flange embracing the blade base, and a gas-deflecting washer interposed between said base and the end of the thimble, together with means associated with said base flange to hold the blade in predetermined relative rotary position with respect to the fuse casing. 100

4. In a cartridge fuse, a substantially closed fuse chamber having an exit for the fuse strip, a blade terminal having a base flange adapted to bear against an offset end of the fuse strip, a thimble encasing said blade base and the end of the fuse chamber, and a ferrule enclosing the thimble and base of the blade terminal and serving to hold the parts assembled at the end of the fuse chamber, together with a gas-deflecting 115 washer arranged between the base flange of the blade and the end of the thimble. 120

5. In a cartridge fuse, a substantially closed fuse chamber having an exit for the fuse strip, a blade terminal having a base flange adapted to bear against an offset end of the fuse strip, a thimble encasing said blade base and the end of the fuse chamber, and a ferrule surrounding the thimble and base of the blade terminal and serving to 130

hold the parts assembled at the end of the fuse chamber, together with positioning stud means at the end of the fuse chamber, and cooperating engaging means on the base 5 flange of the fuse blade.

6. In a cartridge fuse, a substantially closed fuse chamber having an exit for the fuse strip, a blade terminal having a base flange adapted to bear against an offset end 10 of the fuse strip, a thimble encasing said blade base and the end of the fuse chamber, and a ferrule surrounding the thimble and base of the blade terminal and serving to hold the parts assembled at the end of the 15 fuse chamber, together with positioning stud means at the end of the fuse chamber, the base flange of the fuse blade having recesses loosely engaging said stud means to position the blade and to afford venting 20 apertures for the gases generated in the fuse chamber on the blowing of the fuse.

7. In a cartridge fuse, a fuse casing and end bushing fast thereon and having an end opening for the exit of the fuse strip, a fuse 25 terminal adapted to freely bear on the bent-over end of said fuse strip supported on said bushing; gas deflecting means, and an end

cap or thimble associated therewith and forming a removable unit, together with a ferrule for holding said terminal unit assembled with the bushing. 30

8. In a cartridge fuse, a tubular casing forming a fuse chamber with fuse exits at opposite ends thereof, means forming an expansion chamber at one end of the casing, a 35 distortable light metal member impeding the escape of gases from said expansion chamber, and a screw ferrule for holding said impeding member in obstructing position. 40

9. In a cartridge fuse, the combination of a fuse casing, a bushing secured in the end thereof, said bushing having a reduced end, in combination with a removable thimble or cap snugly fitting said reduced 45 end of the bushing and serving to obstruct the escape of gases from the fuse chamber, in combination with means for holding said thimble in obstructing position, said thimble being distortable to permit the escape of 50 gases through a vent in the end thereof.

In testimony whereof I have signed my name to this specification.

ARCHIBALD GRIEVE.
